UNITED STATES PATENT OFFICE.

CHARLES HAMMER, OF QUEENS, NEW YORK, ASSIGNOR, BY DIRECT AND MESNE ASSIGNMENTS, TO AMERICAN METAL CAP CO., OF BROOKLYN, NEW YORK.

FORMATION OF BOTTLE-CAPS.

1,241,509.

Specification of Letters Patent.

Patented Oct. 2, 1917.

Application filed August 30, 1916. Serial No. 117,602.

To all whom it may concern:

Be it known that I, CHARLES HAMMER, a citizen of the United States, residing at Queens, in the county of Queens and State 5 of New York, have invented certain new and useful Improvements in Formation of Bottle-Caps, of which the following is a specification.

This invention relates to the construction 10 of bottle closures, especially to the kind used on bottles which contain catsup and similar liquids. The invention pertains particularly to the character of a closure in which the side or body is formed of a strip of 15 thin sheet metal curved into the proximate shape of a cylinder, with the ends of the strip lapping; and which form is provided with a disk suitably secured at its edge to one end of the cylinder. The object of the 20 invention is to provide special means integral with the lapping ends of the cylinder for securing them together or holding them in position, until the cap end is secured to the cylinder. A further object is to provide 25 such locking means, that will be reinforced by forming a bent edge at the open end of the cylinder.

In the accompanying drawings illustrating 30 the embodiments of my invention, Figure 1 shows a plan and Fig. 2, an edge view of a blank for the body. Fig. 3 shows the blank partly joined at the ends. Fig. 4 is a section on the line 4—4 of Fig. 3. Fig. 5 shows the body and end member assembly. Fig. 6 shows the finished cap.

In Figs. 1 and 2 I show a blank 15 in the form of a flat strip of thin sheet metal having near one end, one or more lugs. As shown I provide lugs 16 and 17 in the blank 40 formed by slits 18 and 19, whereby a substantially square lug is formed by bending the metal between the slits as indicated in Fig. 2. Suitably engaging means is provided at the other end of the blank whereby 45 when the blank is bent into the form of a cylinder with lapping ends, as indicated in Fig. 3, these ends will be held together. In this form I bend the end back on the line 20 to form a hook shaped bend 21 as shown 50 in Fig. 2, and this bend is caused to engage the inner face of the outer portion beneath the inwardly bent lugs 16 and 17, as clearly

shown in Figs. 3 and 4. When these parts are strongly pressed together they will form a closed meeting edge as indicated in Fig. 55 and hold the blank in the cylindrical form.

An end member or disk 22 is suitably secured to one end of the cylinder, as shown in Figs. 5 and 6. This can be done by any of the well known means such as interlocking the edge of the disk with the edge of the cylinder. This will produce a finished cap as shown in Fig. 5. If desired the open end of the cylinder may have the edge doubled back as shown at 23 and which doubled 60 portion includes the adjacent lug 16. This form of cap may be provided with the usual threaded bent portions 24 adapted to cause it to engage the threads on the bottle neck in the usual manner. The cap may be further provided with longitudinal corrugations between the threads and the top which corrugations include the upper lug 17 that has the effect of strengthening the connection at such portion. 75

It will be seen that on the inner face or wall, the bent edge 21 lies between the outer lapping edge and its adjacent cylindrical portion, so that the raw edge is entirely protected from engaging with the bottle. This 80 is very desirable as a raw edge is likely to be free from the coating or enamel on the body portion of the cylinder, and hence might become corroded from the contents of the bottle. 85

It will be further seen that the securing means for the body is entirely integral with the blank for the cylinder, and is easily formed by merely providing the slits at one end and slightly raising the intermediate portion to form the lugs; while the other end of the blank is merely bent back on itself to form a kind of lug extending through the end. Then the blank is bent into the form of a cylinder slightly smaller 90 than the final form and the two lugs cause it to enter the angle of the bent end and then the cylinder slightly expanded and compressed at the meeting ends. The blank will be securely held in this cylindrical position until the application of the disk to close one end nearest the opening and can be beaded or otherwise reinforced. A portion of the bead 21 is cut away, as at 2, so that 100

when the end 39 is applied the doubled fold will not interfere with the locking of the end disk.

It will be readily seen that in the several forms, the securing means for the cylinder are simply bent, or bent and cut, portions of the ends of the strip, that are readily caused to engage or interlock by merely bending the blank into the cylinder form.

10 While these constructions act as a temporary holding means until the end member is secured in position, they also strongly assist in retaining the body of the cap in its final position.

15 Having thus described my invention what I claim is:—

1. A closure cap comprising a body portion formed of a sheet metal strip bent into the proximate form of a cylinder with the 20 end portions lapping and the inner edge being given a single bend back on itself outwardly and lying beneath the lapping unbent cylindrical outer edge to conceal the raw edge and prevent its access from the inside of the cap, the outer lapping portions being provided with integral locking means, and an end member closing one end of the cylinder.

2. A closure cap comprising a body portion formed of a sheet metal strip bent into the proximate form of a cylinder with the 30 end portions lapping and the inner edge being given a single bend back on itself outwardly and lying beneath the lapping unbent cylindrical outer edge to conceal the raw edge and prevent its access from the inside of the cap, the outer lapping portions being provided with locking means in the 35 form of a lug, and an end member closing one end of the cylinder.

3. A closure cap comprising a body portion formed of a sheet metal strip bent into the proximate form of a cylinder with the 45 end portions lapping and the inner edge bent back on itself outwardly and lying beneath the lapping unbent cylindrical outer edge to conceal the raw edge and prevent its access from the inside of the cap, an end member closing one end of the cylinder, the open end 50 of the cap being rolled into a bead, and integral locking means at said lapping portions that is included in said beaded end portion.

4. A closure cap comprising a body portion formed of a sheet metal strip bent into the proximate form of a cylinder with the 55 end portions lapping and the inner edge bent back on itself outwardly and lying beneath the lapping unbent cylindrical outer edge to conceal the raw edge and prevent its access from the inside of the cap, an end member closing one end of the cylinder, the open end 60 of the cap being rolled into a bead, and in-

tegral locking means in the form of a lug at said lapping portions that is included in said 65 beaded end portion.

5. A closure cap comprising a body portion formed of a sheet metal strip bent into the proximate form of a cylinder with the end portions lapping and the inner edge bent 70 back on itself outwardly and lying beneath the lapping unbent cylindrical outer edge to conceal the raw edge and prevent its access from the inside of the cap, the outer lapping portions being provided with an integral lug 75 that projects rearwardly beneath the said folded edge to lock the edges together, and an end member closing one end of the cylinder.

6. A closure cap comprising a body portion formed of a sheet metal strip bent into the proximate form of a cylinder with the end portions lapping and the inner edge bent back on itself outwardly and lying beneath the lapping unbent cylindrical outer edge to 85 conceal the raw edge and prevent its access from the inside of the cap, the outer lapping portions being provided with an integral lug that projects rearwardly beneath the said 90 folded edge to lock the edges together, and an end member closing one end of the cylinder, the open end of the cap being rolled into a bead that includes said lug.

7. A closure cap comprising a body portion formed of a sheet metal strip bent into 95 the proximate form of a cylinder with the end portions lapping and the inner edge bent back on itself outwardly and lying beneath the lapping unbent cylindrical outer edge to conceal the raw edge and prevent its 100 access from the inside of the cap, an end member closing one end of the cylinder, and integral locking means at said lapping portions to secure the edges together, the cylindrical portion being corrugated at the 105 lower end to form a screw-thread including the said lapping portions.

8. A closure cap comprising a body portion formed of a sheet metal strip bent into the proximate form of a cylinder with the 110 end portions lapping and the inner edge bent back on itself outwardly and lying beneath the lapping unbent cylindrical outer edge to conceal the raw edge and prevent its 115 access from the inside of the cap, the outer lapping portions being provided with an integral lug that projects rearwardly beneath the said folded edge to lock the edges together, and an end member closing one end 120 of the cylinder, the open end of the cap being rolled into a bead that includes said lug, the cylindrical portion being corrugated to form a screw thread including the lapping portions and the beaded edge.

CHARLES HAMMER.
